UNITED STATES PATENT OFFICE.

BURTON D. KNICKERBOCKER, OF CHICAGO, ILLINOIS, ASSIGNOR OF ONE-HALF TO EDWARD H. KNICKERBOCKER, OF FAIRFAX, IOWA.

BATH-BRUSH.

SPECIFICATION forming part of Letters Patent No. 666,759, dated January 29, 1901.

Application filed October 23, 1895. Serial No. 566,587. (No model.)

To all whom it may concern:

Be it known that I, BURTON D. KNICKERBOCKER, a citizen of the United States, residing at Chicago, in the county of Cook and State of Illinois, have invented a certain new and useful Improvement in Bath-Brushes, (Case No. 1,) of which the following is a full, clear, concise, and exact description, reference being had to the accompanying drawings, forming a part of this specification.

My invention relates to bath brushes or scrubbers, its object being to provide an improved construction of brush whereby water may be continuously supplied to the surface of the brush, the supply being uniform throughout the surface.

In accordance with my invention I provide a rubber bath-brush formed of a single and integral piece of soft rubber and comprising a pair of thin flexible plates separated by a rim extending around the perimeters thereof to thus form an interior receptacle for the liquid, said receptacle being provided with a duct at a suitable position, by means of which the liquid may be admitted to the interior of the receptacle. One of the said plates is provided upon the outer surface with a series of projections or teeth constituting the scrubbing-surface, and said teeth are provided with axial bores or ducts extending therethrough and communicating with said interior receptacle, whereby the liquid may be delivered to the scrubbing-surface of the brush. A suitable handle is associated with the body of the brush, so that the hand may be readily placed in position to flex or bend the brush into the desired position to fit the contour of the body.

I will describe my invention by reference to the accompanying drawings, in which—

Figure 1 is a view in elevation, partially in section, of a brush embodying my invention. Fig. 2 is a plan view thereof. Fig. 3 is a view looking at the under side of the brush.

Like letters refer to like parts in the several figures.

The brush is formed of rubber or other flexible material and is provided with an interior chamber or receptacle *a*. A tube *a'* is molded with the brush, preferably upon the side, and forms a duct, whereby water may be

admitted to the receptacle *a*. A series of projections or teeth *b b'* are provided upon the face of the brush, the teeth being long enough so that they will possess considerable flexibility 55 and situated close enough together so that they form an efficient scrubbing-surface. The teeth are preferably slightly tapered and somewhat flattened upon the ends. The flattening of the ends of the teeth affords a frictional surface which lends a desirable scrubbing quality to the brush, while the slight taper to the teeth prevents the accumulation of dirt and foreign matter between the teeth and upon the ends. Extending longitudinally 60 through the teeth are ducts *b' b'*, communicating with the receptacle *a*, the ducts extending to the tips of the teeth, whereby the water within the receptacle may flow through the ducts to the ends of the teeth that constitute the scrubbing-surface. The water may thus be continuously supplied in the quantity desired at the contact-surface of the brush—that is, at the surface to be cleaned or scrubbed. Furthermore, the water is by this 65 means uniformly supplied over the whole surface of the brush, and is therefore more effective than though it were supplied in a larger quantity at one point of the brush.

A handle *c*, of any desired form and construction, may be provided upon the back of the brush and preferably takes the form of a strip of rubber, the ends of which are formed integral with the back of the brush, and between which strip and the back the hand is 80 adapted to rest. The tube *a'*, extending from the brush, may be joined with a hose or may be made integrally therewith, as may be found most convenient. I preferably join the tube *a'* with a hose *d* by means of a connector *e*, 85 provided with a bore for the passage of the water, and provided upon its periphery with a centrally-situated channel having walls or shoulders which prevent the tubes from withdrawing from the connector due to the force 90 of the water.

Having described my invention, what I claim as new, and desire to secure by Letters Patent, is—

A rubber bath-brush formed of a single 100 and integral piece of soft rubber and comprising a pair of thin flexible plates sepa-

rated by a rim extending around the perimeters thereof thereby forming an interior receptacle, said receptacle being provided with a duct for the entrance of liquid, one of said 5 plates having upon the outer surface a series of projections or teeth constituting the scrubbing-surface and provided with axial bores or ducts extending therethrough and communicating with said interior receptacle, and a 10 suitable handle associated with the body of

the brush to permit the same to be flexed or bent into any desired position, substantially as described.

In witness whereof I hereunto subscribe my name this 19th day of October, A. D. 1895. 15

BURTON D. KNICKERBOCKER.
